UNITED STATES PATENT OFFICE.

ISSACHAR W. DOEG, OF NEWMARKET, NEW HAMPSHIRE.

PAWL.

SPECIFICATION forming part of Letters Patent No. 725,682, dated April 21, 1903.

Application filed September 17, 1902. Serial No. 123,723. (No model.)

To all whom it may concern:

Be it known that I, ISSACHAR W. DOEG, a citizen of the United States, and a resident of Newmarket, county of Rockingham, State of New Hampshire, have invented an Improvement in Pawls, of which the following description, in connection with the accompanying drawings, is a specification, like characters on the drawings representing like parts.

10 This invention has for its object the production of a novel pawl adapted to coact with a ratchet-wheel and control the movement thereof. My novel pawl is of especial advantage in connection with looms, as by it greater 15 accuracy may be obtained in weaving, and its use is particularly valuable in connection with the take-up and let-off of looms in insuring uniformity in the texture of the cloth being woven.

20 Cast-iron pawls are commonly employed with cast-iron ratchet-wheels, and the wear of pawl and wheel show in the woven cloth.

To increase the durability and effectiveness of the pawl and insure greater accuracy of 25 movement of the parts depending upon the pawl, I have provided the body of the pawl with a detachable plate having a plurality of acting edges that may be used one after the other whenever any wear becomes manifest.

30 Figure 1 shows a sufficient portion of a loom with a take-up ratchet-wheel and one of my pawls in coacting relation therewith. Fig. 2 shows the pawl enlarged, detached, and broken out at one end. Fig. 3 shows an under-side view of the acting end of the pawl, and Fig. 4 shows separately the plate and the bolt used to attach it to the pawl-body.

35 A represents a portion of a loom-frame; B, the lay; C, the take-up ratchet; D, the pawl-carrying lever, and E one of my novel pawls. The pawl-carrying lever D may be moved in any usual manner and be of any usual shape, the said lever as herein represented being actuated from a link G, connected with the 40 lay, the latter being movable about the lay rock-shaft H.

The pawl-body may be of any usual or suitable shape.

45 The pawl herein shown is provided at its side nearest the ratchet-wheel with a flat face a, with a hole b, and with a notch c, the lat-

ter being at the outer side of the pawl-body, as best shown in Fig. 2. The flat face a in accordance with my invention acts to support the back 2 of the plate d, having a plurality 55 of acting edges 3 4 5 6, either one of which may be exposed at the extremity of the pawl and engage a ratchet-tooth. That edge of the plate opposite the one in engagement with the pawl contacts with the shoulder e at one 60 edge of the flat surface a. That either edge of the plate d may be readily brought into operative position at the acting end of the pawl-body I have provided the plate with a central hole 7, and the portion of said hole at 65 the outer side of the plate, or the side nearest the ratchet-wheel, is countersunk to leave a space 8 for the reception of the head 9 of a screw 10, the shank of which, projecting from the hole 7, enters the hole b of the pawl-body 70 and has applied to it a nut 12, said nut entering the notch c in the outer face of the pawl-body. By embedding the head of the bolt in the face of the plate the bolt is prevented from contacting with the ratchet-teeth, and 75 owing to the bolt being located at the center of the plate when the nut is unscrewed sufficiently to enable the bolt to be withdrawn permits the plate to be moved for a quarter-turn to bring an unused edge in operative position.

A pawl having a plate provided with a plurality of acting edges will last very much longer than a pawl having but one edge, and by using a plate of steel of the class described 85 it is possible to get metals of different hardness coacting together, which always results in greater durability.

Having fully described my invention, what I claim as new, and desire to secure by Letters 90 Patent, is—

1. A pawl-body having a flat face and a notch on its free end, a detachable contact-plate provided with a plurality of working edges seated upon the flat face of the pawl-body, and a bolt passing centrally through the contact-plate and the end of the pawl-body, and a nut on said bolt seated in the notch in the outer end of the pawl-body. 95

2. A pawl-body provided with a flat face 100 and a notch near the end thereof, one edge of said flat face presenting a shoulder, a detach-

able contact-plate provided with a plurality of beveled working edges, and a bolt passing through the end of the pawl-body and centrally of the contact-plate for securing said contact-plate in position on the flat face of the pawl-body with one edge bearing against said shoulder, and a nut on said bolt seated in said notch.

In testimony whereof I have signed my name to this specification in the presence of 10 two subscribing witnesses.

ISSACHAR W. DOEG.
